UNITED STATES PATENT OFFICE

GEORGE U. CARTER, OF ORANGE, CALIFORNIA

TUBE PASTE DISPENSER

Application filed June 29, 1932. Serial No. 620,016.

The present invention relates to a tube paste dispenser and has for its primary object to provide, in a manner as hereinafter set forth, a device of this character embodying a novel construction, combination and arrangement of parts through the medium of which substantially all of the contents of a collapsible tube may be ejected as desired in a convenient manner.

10 Other objects of the invention are to provide a tube paste dispenser of the aforementioned character which will be simple in construction, strong, durable, efficient and reliable in use, compact, attractive in appearance and which may be manufactured at low cost.

20 All of the foregoing and still further objects and advantages of the invention will become apparent from a study of the following specification, taken in connection with the accompanying drawings wherein like characters of reference designate corresponding parts throughout the several views, and wherein:—

25 Figure 1 is a view in front elevation of a tube paste dispenser constructed in accordance with the present invention.

Figure 2 is a view in vertical section through the device.

30 Figure 3 is a view in horizontal section, taken substantially on the line 3—3 of Figure 2.

Figure 4 is a detail view in elevation showing the means for operatively connecting the 35 vertically movable frame and spool to the actuating shaft which is provided therefor.

Figure 5 is a detail view in vertical section, taken substantially on the line 5—5 of Figure 2.

40 Figure 6 is a fragmentary detail view in perspective, showing a portion of the spool.

Figure 7 is a detail view in vertical section, taken substantially on the line 7—7 of Figure 2.

45 Figure 8 is a detail view in bottom plan of the nozzle.

Figure 9 is a detail view in side elevation showing a spring motor which may be used for ejecting the paste in lieu of hand power.

50 Referring now to the drawings in detail, it

will be seen that the dispenser constituting the present invention comprises a metallic housing 1 which is secured in position on a wall or other vertical support, as at 2. The front of the housing 1 is closed by a door 3 which is hinged at 4 and which is equipped with a suitable latch 5.

Mounted horizontally in the housing 1 are upper and lower plates 6 and 7, respectively. Spaced, vertical guide rods 8 and a spirally grooved shaft 9 extend between the plates 6 and 7. Journaled horizontally in the housing 1 above the plate 6 is a drive shaft 10 which is operatively connected to the shaft 9 by beveled gears 11. One end of the shaft 10 projects from the housing 1 and has fixed thereon a hand knob or wheel 12.

The reference numeral 13 designates a horizontally disposed, substantially U-shaped frame which is mounted for vertical movement in the housing 1 on the guide rods 8 and the shaft 9. One end portion of the frame 13 is bifurcated, as at 14, to provide a space for the accommodation of a worm gear 15 which is operatively connected to the shaft 9 for actuation by said shaft through the medium of a key or lug 16 which is engaged in the spiral groove of the shaft. This key or lug is designated by the reference numeral 16.

Journalled horizontally in said one end portion of the frame 13 is a sleeve 17 having formed integrally therewith a worm gear 18 which is in mesh with the worm gear 15. A diametrically extending pin 19 is mounted in the sleeve 17 for a purpose to be presently set forth.

Journalled horizontally in the frame 13 is a slidably removable spool 20 having a slot 21 extending longitudinally thereinto from one end thereof. On the other end of the spool 20 is fixed a knob 22. When in operative position, said one end of the spool 20 is engaged in the sleeve 17, the slot 21 receiving the pin 19 for connecting said spool to the sleeve for actuation thereby. The slot 21 also receives the closed end portion of the collapsible tube, one of which is designated by the reference numeral 23.

The reference numeral 24 designates a ta-

pered nozzle having a reduced neck 25 thereon which is threadedly engaged in an opening provided therefor in the plate 7. The neck 25 is also internally threaded for receiving the neck 26 of the tube 23. The outlet of the passage in the nozzle 24 is substantially slot-shaped, as at 27 (see Figure 8). The nozzle 24 depends from the housing 1 through an opening 29 provided therefor in the bottom of said housing.

If desired, a spring motor 30 of substantially conventional construction may be mounted in the upper portion of the housing 1 for actuating the shaft 9. The spring motor 30 is operatively connected to the shaft 9 by gears 31 in which is included a manually operable reversing gear permitting the shaft to be actuated in opposite directions to raise or lower the frame 13 and to rotate the spool 20 in opposite directions. The reference numeral 32 designates a winding key for the motor 30 which is insertable through an opening provided therefor in the top of the housing.

25 In use, the frame 13 is raised to the upper portion of the housing 1 and the tube 23 is inserted in said housing. The neck 26 of the tube 23 is threaded into the neck 25 of the nozzle 24 and the closed end portion of said tube 23, which is now uppermost, is inserted in the slot 21 of the spool 20. Then, the shaft 9 is actuated, either by the drive shaft 10 or the spring motor 30, to rotate the spool 20 for winding the tube 23 thereon, as illustrated in Figure 2 of the drawings, thus ejecting the contents of said tube 23. At the same time, the frame 13 is moved downwardly on the guide rods 8 by reason of the engagement of the key or lug 16 in the 30 spiralled groove of the shaft 9. To raise the frame 13, the direction of rotation of the shaft 9 is reversed. A suitable cut-off valve (not shown) may be provided in the nozzle 24 for controlling the discharge of the paste, particularly when the spring motor 30 is being used.

It is believed that the many advantages of a tube paste dispenser constructed in accordance with the present invention will be readily understood, and although the preferred embodiments of the invention are as illustrated and described, it is to be understood that changes in the details of construction and in the combination and arrangement of parts may be resorted to which will fall within the scope of the invention as claimed.

What is claimed is:—

1. A tube paste dispenser comprising a 60 housing, guide rods mounted in the housing, a drive shaft rotatably mounted in the housing in spaced parallelism with the guide rods, said drive shaft having a spiral groove therein, a frame slidably mounted on the 65 guide rods and on the drive shaft, the end

portion of the frame which is engaged with the drive shaft being bifurcated, a worm gear mounted on the drive shaft and having its ends engaged with the bifurcations of the frame, a key on the worm gear engaged in the groove of the drive shaft, a sleeve journaled for rotation in said one end portion of the frame, a gear on the sleeve engaged with the first named gear for actuation thereby, means for actuating the drive shaft, and a spool journaled in the frame and operatively connected with the sleeve for actuation by said sleeve, said spool being connectible with the tube for winding said tube thereon.

2. A tube paste dispenser comprising a 80 housing, guide rods mounted in the housing, a drive shaft mounted for rotation in the housing in spaced parallelism with the guide rods, said drive shaft having a spiral groove therein, means for actuating the drive shaft, a substantially U-shaped frame slidably mounted on the guide rods and on the drive shaft, one end portion of the frame being engaged with the drive shaft and being bifurcated, a worm gear mounted on the drive shaft and having its ends engaged with the bifurcations of the frame, a key on the worm gear engaged in the groove of the drive shaft for connecting said gear to the drive shaft for longitudinal actuation thereby, a sleeve rotatably mounted in the frame, a gear on the sleeve engaged with the first named gear, a spool rotatably mounted on the frame and having one end portion engaged in the sleeve, said spool having a longitudinal slot extending thereinto from said one end thereof for the reception of an end portion of the tube for connecting said tube to the spool for winding thereon, and a diametrically extending pin in the sleeve engaged in the slot 90 for connecting the spool to said sleeve.

3. A tube paste dispenser comprising a 100 housing guide rods mounted in the housing, a drive shaft mounted for rotation in the housing in spaced parallelism with the guide rods, said drive shaft having a spiral groove therein, means for actuating the drive shaft, a substantially U-shaped frame slidably mounted on the guide rods and on the drive shaft, one end portion of the frame being engaged with the drive shaft and being bifurcated, a worm gear mounted on the drive shaft and having its ends engaged with the bifurcations of the frame, a key on the worm gear engaged in the groove of the drive shaft for connecting said gear to the drive shaft for longitudinal actuation thereby, a sleeve rotatably mounted in the frame, a gear on the sleeve engaged with the first named gear, a spool rotatably mounted on the frame and having one end portion engaged in the sleeve, said spool having a longitudinal slot extending thereinto from said one end thereof for the reception of an end portion of the tube for connecting said tube to the spool for wind- 110

ing thereon, and a diametrically extending pin in the sleeve engaged in the slot for connecting the spool to said sleeve, said means including a shaft rotatably mounted in the housing at right angles to the drive shaft, gears connecting the drive shaft to the second named shaft for actuation thereby, and a knob fixed on the second named shaft for manually actuating said second named shaft.

10 4. A tube paste dispenser comprising a housing, guide rods mounted in the housing, a drive shaft mounted for rotation in the housing in spaced parallelism with the guide rods, said drive shaft having a spiral groove

15 therein, means for actuating the drive shaft, a substantially U-shaped frame slidably mounted on the guide rods and on the drive shaft, one end portion of the frame being engaged with the drive shaft and being bifurcated,

20 a worm gear mounted on the drive shaft and having its ends engaged with the bifurcations of the frame, a key on the worm

gear engaged in the groove of the drive shaft for connecting said gear to the drive shaft for longitudinal actuation thereby, a sleeve rotatably mounted in the frame, a gear on the sleeve engaged with the first named gear, a spool rotatably mounted on the frame and having one end portion engaged in the sleeve, said spool having a longitudinal slot extending thereinto from said one end thereof for the reception of an end portion of the tube for connecting said tube to the spool for winding thereon, and a diametrically extending pin in the sleeve engaged in the slot for connecting the spool to said sleeve, said means including a spring motor mounted in the housing, and gears operatively connecting the drive shaft to the spring motor for actuation thereby.

25 In testimony whereof I affix my signature.

GEORGE U. CARTER.
